PULL

Raymond Tintary, Covina, and Anthony Joseph Carsello, Hollywood, Calif., assignors to Ajax Hardware Manufacturing Corp., a corporation of California

Filed Mar. 3, 1965, Ser. No. 84,067

Term of patent 14 years

(Cl. D10—8)

FIG. 1 is an isometric view of the pull of our design;
 FIG. 2 is a front elevational view;
 FIG. 3 is a top plan view;
 FIG. 4 is a rear elevational view;
 FIG. 5 is an end elevational view; and
 FIG. 6 is a vertical cross-sectional view taken on line 6—6 of FIG. 2.

We claim:

The ornamental design for a pull, as shown.
